UNITED STATES PATENT OFFICE

161,227

STROLLER

James T. Wheeler, Atlanta, Ga.

Application March 4, 1948, Serial No. 144,903

Term of patent 3½ years

(Cl. D14—14)

To all whom it may concern:

Be it known that I, James T. Wheeler, a citizen of the United States of America, residing at Atlanta, in the county of Fulton and State of Georgia, have invented a new, original, and ornamental Design for a Stroller, of which the following is a specification, reference being had to the accompanying drawing, forming a part thereof.

In the drawing:

I claim:

The ornamental design for a stroller, as shown.

JAMES T. WHEELER.
